DOOR CALL

Filed Nov. 20, 1931

Fig. 1.

Fig. 1.

Fig. 3.

The diagram illustrates a mechanical assembly, possibly a gear train or a similar transmission system. It features several components labeled with numbers:

- 15: A small rectangular part at the bottom left.
- 10: A large gear at the bottom center.
- 11: A circular component with a cross-hatch pattern, located near the center.
- 12: A rectangular component with a slot, positioned above the gear 10.
- 13: A gear with a central hole, located below gear 10.
- 14: A rectangular component with a slot, positioned below gear 13.
- 16: A small rectangular part at the bottom center.
- 17: A gear with a central hole, located below gear 14.
- 18: A rectangular component with a slot, positioned above gear 17.
- 19: A gear with a central hole, located below gear 18.
- 20: A rectangular component with a slot, positioned above gear 19.
- 21: A circular component with a cross-hatch pattern, located near the center.
- 22: A large gear at the top center.
- 23: A rectangular component with a slot, positioned above gear 22.
- 24: A small rectangular part at the top left.

The components are interconnected in a vertical sequence, with gears meshing together and rectangular parts likely serving as bearings or supports.

INVENTOR.
Eugene A. Hoag.

Francis H. Davis.
ATTORNEY.

UNITED STATES PATENT OFFICE

EUGENE A. HOAG, OF PACIFIC GROVE, CALIFORNIA

DOOR CALL

Application filed November 20, 1931. Serial No. 576,405.

This invention relates to a door call and for the purpose of this disclosure is described and illustrated as a manually-operated, mechanical woodpecker, arranged to deliver a rapid succession of loud taps on a resonator.

In the present instance my novel device is represented as being secured to the outer surface of a door, to act as a call. Obviously my invention may be applied to many other uses, such for instance as an ornamental desk buzzer to act as a call, or it may be used as a toy.

The structure of the bird-like body may be either of carved wood, where a craft-man-like effect is desired for the more expensive devices, or it may be molded from any suitable material such as papier-mâché.

In the present instance the bird body is shown as a two-piece stamping comprising a boat-like breast member adapted for attachment to a plate, and a back member which fits over the breast member like a cover, suitable locking-means being provided to hold said members together when united.

The objects of my invention comprise the following desiderata:—

To provide a novel and attractive device resembling a woodpecker, for attachment to a door or other resonant object and having means to simulate the rapid tapping of a woodpecker on a hollow tree.

To provide means to secure the bird structure to a relatively fixed structure.

To provide a hollow body having internal mechanism adapted to vibrate a bird's head against a plate or stud when operated by an external turnable knob.

To provide a manually-operable knob at the right hand side of the bird's body arranged to be twirled clock-wise by a user's right hand when standing facing the device.

To provide a vibratory, curved stem extending forward in a beak-like manner from a detent-controlled rock-shaft, and a bird's head of suitable cementitious matter molded on the stem so that the end of the stem forms a hammer to beat against a plate or stud.

In the accompanying drawing,

Figure 1 is a side elevational view of my device attached to a vertical resonator.

Figure 2 is a front elevational view.

Figure 3 is a front elevational view of the vibratory mechanism.

Figure 4 is a section taken on the line IV—IV of Figure 3, and through the head.

Figure 5 is a section taken on the line V—V of Figure 1.

Figure 6 is a side elevational view of the member forming the bird's back.

Similar reference indicia refer to similar parts throughout the several views.

In carrying out my invention I provide the concaved breast member 7 secured to the resonator 5 by the screws or bolts 6—6.

The structure 7 is adapted to receive the clock-work unit C attached to the interior wall thereof by the lugs 9 and the screws 9'.

The unit C comprises the respective side frame members 10—10' spaced apart and secured by the respective posts 11, suitably nutted or riveted. The main winding stem 13 extends outwardly through the lapped members of 7 and 8 at 14, and carries the knob 15.

The master gear 16 fast to the stem 13 meshes with the lantern pinion 17 secured to the adjacent side of the escapement wheel 18 fast to the shaft 19 and nicely journaled in said frames. The detent 20 rocks on the shaft 21, also journaled in said frames.

The stem 22 carried by the shaft 21 mounts the head 23 which may well be moulded thereon and composed of any suitable cementitious composition.

The coil spring 29 surrounds the shaft 21 and is adapted and arranged, normally and yieldingly, to hold the head 23 in the backward position, in which disposition the neck 24 overlaps the adjacent portions of the body members 7 and 8 so as to exclude rain or snow which may beat upon it.

It will be noted that the bounding edges of the member 7 are struck inwardly so as to leave the seat 26 for the companion edges of the member 8 to abut against; the creases 27 being provided adjacent the edges of said member to inter-engage complementary creases forward on the member 7, thereby constituting locking means for binding said members together along the curved line 28.

which simulates the rounded outer edge of a folded wing.

When the knob 15 is twirled between finger and thumb in a clock-wise direction the gear 16 acts on the lantern pinion 17, thus rotating the escapement pinion 18 thereby imparting rocking motion to the shaft 21 through the detent 20, this in turn imparts a rapid vibratory motion to the stem 23 causing the end of the beak 22' to sound a loud tattoo by striking against the anvil 25.

I have shown the element C as a preferred means for producing the woodpecker sound by my device but obviously other reciprocating means could be employed without departing from the spirit of the invention, or the scope of the appended claims.

I claim:—

1. In a device of the character described, a pair of shell-like body members having overlapping meeting edges forming an inclosure, a frame supported within the inclosure, and carrying a springless gear train including an escapement lever, a member associated with the escapement lever and movable therewith, and a shaft extending through the overlapped edges at one side of the inclosure to retain the body members in assembled relation and providing a rotatable support for the drive gear of the train.
2. In a device of the character described, a hollow body member, a frame within the body member carrying spaced lugs for attachment to the body member, a springless gear train supported on the frame and including an escapement lever, a member associated with the escapement lever and movable therewith and a shaft journaled in the frame and extending through one side of the body member and providing a rotatable support for the manually operated drive gear of the train and said body member carrying a base plate to facilitate attachment to a support.
3. In testimony whereof I affix my signature this 14th day of November, 1931.

EUGENE A. HOAG.
